ATTACHMENT TO MACHINES FOR FORMING
PULPAvenon S. Viger, near Shelton, Wash., assignor to
Lamb-Grays Harbor Company, Hoquiam,
Wash., a corporation of Washington

Application April 18, 1952, Serial No. 282,937

6 Claims. (Cl. 92—43)

1

The present invention relates to a machine for forming pulp as a blanket upon a large drum or cylinder, usually termed a mold, whether at the stage where the pulp is being washed or at the stage where the pulp is formed as a blanket of endless length preparatory to forming a web, and specifically to an attachment to such a machine whereby liquid expressed from the web by a dewatering roll is intercepted, and is directed to a discharge point where it will not reenter the pulp blanket.

In such an operation water or liquor is expressed from the blanket of pulp as it passes upwardly from a pulp vat on the peripheral surface of the large mold, by the action of a dewatering roll that presses the pulp blanket between itself and the mold's periphery. Such dewatering rolls express the water by pressure, but in addition such dewatering rolls temporarily collect the expressed water in pockets for subsequent discharge. In some instances it is undesirable to permit the liquid so expressed and collected to drip down into the vat, to dilute the liquor therein, and even when such is not the case it is undesirable to permit the expressed and collected water (as the dewatering roll turns over) to drip down again on the uprunning pulp blanket beneath it. Thus in either instance it is desirable to receive the liquid expressed from the pulp blanket and collected temporarily in the pockets of the dewatering roll, and to direct or convey that liquid for discharge to a point where at least it will not drip down upon the pulp blanket on the mold beneath the dewatering roll, or in other cases to a point where it will be discharged outside the vat. The present invention relates to provisions for so collecting, directing, and discharging the expressed liquid collected in the dewatering roll's pockets.

According to one phase of the present invention the liquid so collected in the pockets of the dewatering roll is extracted or expelled from the pockets by air-pressure means, such, for instance, as positive pressure applied to the pockets before the corresponding peripheral portion of the dewatering roll again contacts the pulp blanket, or by means of suction or negative pressure applied to the pockets after the water has been collected therein, to draw the water from such pockets. The suction and the positive pressure means are but two instances of air pressure means for the purpose, and either, or the two together, may be employed for the purpose.

In either case it is desirable to provide an intercepting means such as a trough to receive,

2

and in some cases to collect, such liquid as can not be extracted or expelled by the air-pressure means, or to collect or to direct away from the mold all the liquid in the event the air-pressure means are not employed, and in the event the return of the liquid to the vat is not objectionable, such a trough need be little more than an intercepting apron. It must be located beneath the dewatering roll and close to the mold, so that it lies generally in the notch between the uprunning lower peripheral portion of the dewatering roll and the uprunning upper peripheral portion of the mold. The present invention is concerned with such an intercepting means, whichever form it may assume, the location of its drain if it take the form of a collecting trough, the manner in which it is fixedly located in proper position, yet can move when necessary, and the manner in which it is supported with relation to the dewatering roll.

More particularly, because of the necessary location of such a trough, close to the mold, it may at times be impinged by a pulp jam in a manner tending to rotate the trough and to urge it more closely into the notch, or to actually move it between the dewatering roll and the mold. According to the present invention provision is made for either preventing or permitting such movement, but in either event for minimizing the damage if such tendency should occur.

The objects of the invention are outlined above, and will become more clearly apparent as this specification progresses.

The present invention comprises the novel attachment to a pulp forming machine and the novel combination and arrangement of the parts thereof, including the standard parts with relation to the interceptor and water expulsion means, and of the latter with respect to one another and with respect to the standard parts of such a pulp forming machine.

In the accompanying drawings the invention is shown in two representative forms, as applied to a typical machine. Figure 1 is an isometric view, partially broken away, illustrating one end of the several rolls and a trough and other parts which cooperate to the ends indicated above. Figure 2 is a fragmentary end elevation, and Figure 3 is a fragmentary side elevation, of a somewhat modified, apron-like form of interceptor.

The mold is a large drum, perhaps eight feet in diameter, the end whereof is represented at 1, and its periphery of mesh-like material is illustrated at 10. This large mold rotates on jour-

nal bearings which have not been illustrated, within a vat, the end wall of which is indicated at 2. Within this vat is a charge of pulp in liquid suspension. By applying suction within the mold 1 while it rotates, pulp collects in an ultimately rather heavy blanket B upon the periphery of the mold, being formed at the uprunning side of the mold's periphery where the mold rises from the surface of the liquor within the vat. In a washing machine, or if the pulp is merely to be formed as a blanket from a single charge, the blanket is carried round and round into and out of the liquor, but where the blanket is the first step in the manufacture of a web of indeterminate length, it may be detached from the mold and carried on thence through various pressing and drying operations. What happens to the pulp after it passes the dewatering roll is not material to the present invention.

The pulp is usually pressed first between a roll 3 and the periphery of the mold 1, this roll 3 being only slightly above the level of the liquid within the vat, and secondarily by a dewatering roll indicated in general by the numeral 4. This dewatering roll has a foraminous peripheral surface, indicated at 40, and interiorly has a plurality of scoop-like vanes 41, directed generally lengthwise and defining a plurality of pockets for the collection and reception of water expressed from the pulp blanket B through the foraminous covering 40. The dewatering roll 4 is mounted upon a shaft 42, supported in a bearing 44 in such manner that the roll may be moved bodily towards or from the mold 1 to vary the amount or degree of pressure, and for other purposes.

Thus the bearing 44 is, in a typical case shown in Figure 1, supported upon a lever 5 which is pivotally mounted at one end, as indicated at 50, upon a bracket 21 which in effect is part of the main frame or wall of the vat, and the opposite end of the lever is connected to a plunger 51 connected to a pressure element within a chamber represented at 52 and having the pressure connections 53 and 54 whereby the position of the lever 5 and consequently of the dewatering roll 4 as a whole may be determined and adjusted from a distant control station. The limit of approach of the roll 4 to the mold may be fixed by an adjustable stop 22, carried by and reacting from the bracket 21.

The dewatering roll 4 is preferably closed at its ends by end plates 43, and in the form of this invention which is shown in Figure 1 these are provided with holes 45 which are arranged in a common circle, and which register with the several pockets between the vanes 41. At 61 a suction chest registers with the circle defined by the holes 45 and is located to communicate with the several holes in the vicinity of and beyond the point where the roll 4 contacts with the pulp blanket B. A similar pressure chest 62 also registers with the circle defined by the holes 45 and is located immediately in advance of the point where the roll 4 contacts with the pulp blanket. By appropriate application of suction to the suction chest 61 or of pressure to the pressure chest 62, or both, these chests, both of which are in reasonably tight sealing engagement with the end plates 43, apply pressure, positive or negative, to the pockets within the interior of the dewatering roll in such a way as to insure, to the highest degree possible, the expulsion or extraction of liquid picked up within these several pockets, before the peripheral por-

tion 40 of the roll adjacent such pockets again contacts with the pulp blanket.

It is clear that these pressure and suction means will to some degree scavenge the several pockets. However, they can draw only from the ends of the pockets, and since the roll 4 is some eight feet long, a great deal of liquid spills from the pockets through the mesh periphery elsewhere than at their ends, as the roll 4 turns over. Accordingly, it is necessary to provide means for the reception and collection of that liquid, whether or not the pressure means are used, and to insure its conveyance to a point where it may be discharged without harm, for if this liquid is permitted merely to drip down upon the uprunning pulp blanket beneath it, or upon the pressure roll 3 beneath it, this liquid will again, in considerable part at least, impregnate the pulp blanket and will again have to be expressed.

Accordingly, in one form of the invention, shown in Figure 1, I provide a trough 7 which is located below the roll 4, and more specifically within the notch between the uprunning lower periphery of the dewatering roll 4 and the uprunning upper periphery of the mold 1. The trough 7, thus located, will catch virtually all the liquid that remains in the pockets of the dewatering roll, and, indeed, when it is used the suction chest 61 and the pressure chest 62 will not be necessary, but may be considered as auxiliaries to the trough. The trough is preferably provided with a soft wiper 73 of rubber, for example, contacting the periphery of the dewatering roll 4 to wipe off any liquid that may still tend to cling to it and to guide that liquid back into the trough. The trough is provided with a drain 71, and it is preferred that this drain be located outside the end of the mold 1. So located, it would permit the liquid collected in the trough to drain back into the vat 2, but not to drip upon the mold nor upon the pulp blanket B collected on the mold's uprunning periphery. However, if it is preferred that the collected liquid be discharged elsewhere than back into the vat, a flexible hose (not shown) connected to the drain at 71 may be provided for the purpose of conducting away and discharging at a proper point the collected liquid.

The trough 7 is preferably supported upon a bracket 72 which hangs the trough from the shaft 42, so that the trough is supported in general coaxially of the dewatering roll 4. In order that the trough may be held steady, a tension member 74 extends from the trough to a fixed support, such, for instance, as the wall of the vat 2, but this member 74 is of fragile or readily broken material, so that in the event of an accidental occurrence as will shortly be described, it can break readily and will not then restrain the movement of the trough 7. Incidentally, the suction chest 61 and the pressure chest 62 may conveniently be supported from the same bracket 72. Furthermore, it will be helpful if the bracket 72 be provided with an elongated aperture 75, through which the shaft 42 passes, so that some radial movement of the bracket and of the elements supported thereby is possible under certain abnormal conditions.

Under normal circumstances the pulp blanket forms upon the periphery 40 of the mold 1, and when it is thick enough it contacts the peripheral surface of the dewatering roll 4, and likewise of the roll 3, and begins to turn these rolls. As the pulp blanket builds up in thickness, the pressure exerted by the pressure

chamber at 52 causes the dewatering roll 4 to press with sufficient pressure to express a large part of the liquid from the blanket B. This operation continues, and under normal circumstances the collected liquid is expressed from the pockets in the dewatering roll, is caught in the trough 7, or is carried off through the suction chest 61, and the pulp-forming operation proceeds normally. However, occasionally a mass or blob of pulp will collect upon the surface of the blanket and will jam into the notch between the roll 4 and the mold 1. Since the trough 7 must be located rather closely to the periphery of the mold within this notch, such an extraordinary mass or blob of pulp may contact the trough 7, and if it does it will tend strongly to rotate the trough along with the roll 4.

Whenever this occurs the restraining element 74 will break, the slot 75 will permit the bracket 72 and the trough 7 to approach very closely to the periphery of the roll 4, and the pressure chamber 52 may be so formed or controlled that it will permit the roll 4 to move away from the mold 1, for example into a position shown by the dot-dash lines in the drawing, and so the trough 7 will pass between the mold 1 and the roll 4 without causing any great amount of damage. Drain hoses, pressure and suction lines, and the like, connected to the trough or to its support, may be flexible and of sufficient length to permit such movement, or may well be arranged to pull off when such an event occurs, and so they are not injured. All that is necessary is to shut down the machine temporarily, to clear the jam, and to relocate the parts which have been moved, and recommence the operation.

The interceptor shown in Figures 2 and 3 is more nearly of the nature of an apron, which intercepts the liquid picked up in the interior pockets of the dewatering roll 4, and which tends to spill out of them as these pockets, after riding over the top of the rotative path of the roll 4, incline downwardly again. Here the apronlike interceptor 76 rests at its lower end upon a fixed spray pipe 8, being held thereto by brackets 77, and at its end nearest the mold 1 and pulp blanket B the interceptor 76 is held with its wiper 70 pressed against the periphery of the dewatering roll 4 by means of a spring 78 anchored to a collar 79 which encircles the shaft 42.

The shaft 42, and thus the dewatering roll 4 as a whole, is in this arrangement supported upon the outer end of a lever 56, pivotally mounted at 57 upon a bracket 58 carried by the vat wall 2, and the position of the lever 56, and consequently the pressure with which the roll 4 presses upon the blanket B, is controlled by an adjustable tension element 59, suspending the lever from a suitable overhead support.

In this arrangement there is no provision for expelling or withdrawing liquid from the pockets within the roll 4. These pockets will remain full until they pass over the top of the rotative path of the dewatering roll, and then as they incline downwardly they will tend to empty through the peripheral mesh 40, and as the roll rotates the liquid will be thrown somewhat inwardly by the centrifugal effect, and would normally wet the blanket B beneath the dewatering roll 4. However, the interceptor 76 being interposed in position to intercept such discharged liquid, and the wiper 70 wiping off any last vestiges that remain on the surface of the roll 4, all this intercepted liquid will drain back down the inclined interceptor 76, and will be discharged into the 75 collected pulp blanket; said dewatering roll in-

vat, but clear of the mold 1 and its blanket B. If discharge back into the vat were undesirable, it is evident that the interceptor 76 might be formed as a trough to collect rather than to drain off the liquid immediately, and it could then be drained off through drains corresponding to that shown at 71 in Figure 1.

It will be observed, too, that in this form of the invention the interceptor 76 is so rigidly supported by the spray pipe 8 that it cannot be drawn into the notch between the peripheries of the roll 4 and mold 1. The lever 56 may yield somewhat upwardly, and so relieve pressure on the blanket B in the event the blanket becomes overly thick or a blob of pulp collects thereon, and in such event the raising of the roll 4 will cause some raising and tilting of the interceptor 76, but the two will always remain more or less in the relative positions shown.

It will be realized that one end only of the machine is shown, because of the limitations of space, but that the suction chest 61 and pressure chest 62, if employed, and in any event the brackets 72 or 77 for the support of the interceptors 7 and 76, respectively, would be duplicated at the opposite end of the machine, and there may be also a duplicate drain 71.

I claim as my invention:

1. In a pulp-forming machine, in combination with a mold of large diameter rotative within the pulp vat to collect a peripheral blanket of pulp and to carry the same to a level above the liquid within the vat, and with a dewatering roll of small diameter located at the uprunning side of the mold's periphery, means journaling the dewatering roll for movement away from and towards the mold, yieldable biasing means normally urging the roll towards and retaining it in operative engagement with the pulp blanket, to express and to pick up liquid from the blanket, a collecting trough, a drain therefrom to a point located within the vat but outside the vertical projection of the mold, means pivotally mounted coaxially of the dewatering roll, for support of said trough to swing upwardly between the mold and the dewatering roll, and easily ruptured means extending between the trough and a fixed support to retain the trough in an operative position within the notch defined between the uprunning lower periphery of the dewatering roll and the uprunning upper periphery of the mold, in which operative position the trough will receive expressed liquid draining from the dewatering roll, but upon rupture of said trough-retaining means said pivotal mounting means permitting the trough to swing upwardly between the two peripheries as they are forced apart, in opposition to the biasing means, by the interposition of the trough.

2. A pulp-forming machine as in claim 1, characterized in that the pivotal mounting means of the trough is formed for generally radial approach of the trough to the dewatering roll in the event of a pulp jam in the notch between the trough and the mold.

3. In a pulp-forming machine, in combination with a pulp vat and with a mold of large diameter rotative within the pulp vat to collect a peripheral blanket of pulp and to carry the same to a level above the liquid within the vat, and with a dewatering roll of small diameter located at the uprunning side of the mold's periphery and co-operating therewith by contact with the pulp blanket to express and to pick up liquid from the

cluding a plurality of longitudinally directed, angularly spaced vanes located adjacent its periphery and defining a plurality of water-collecting pockets, and an end plate closing said pockets but formed with holes admitting to each pocket and located in a common circle, for drainage; and a suction chest contacting the roll's end plate in position to include a number of holes in the vicinity of and immediately beyond the roll's point of contact with the pulp blanket, in the sense of the roll's rotation, to withdraw expressed liquid picked up and collected within the roll's pockets.

4. In a pulp-forming machine, in combination with a pulp vat and with a mold of large diameter rotative within the pulp vat to collect a peripheral blanket of pulp and to carry the same to a level above the liquid within the vat, and with a dewatering roll of small diameter located at the uprunning side of the mold's periphery and co-operating therewith by contact with the pulp blanket to express and to pick up liquid from the collected pulp blanket, said dewatering roll including a plurality of longitudinally directed, angularly spaced vanes located adjacent its periphery and defining a plurality of water-collecting pockets, and an end plate closing said pockets but formed with holes admitting to each pocket and located in a common circle, for drainage; and an air-pressure chest contacting the roll's end plate in position to include a number of holes immediately in advance of the roll's point of contact with the pulp blanket in the sense of the roll's rotation, to expel undrained liquid picked up and collected within the roll's pockets.

5. In a pulp-forming machine, in combination with a pulp vat and with a mold of large diameter rotative within the pulp vat to collect a peripheral blanket of pulp and to carry the same to a level above the liquid within the vat, and with a dewatering roll of small diameter located at the uprunning side of the mold's periphery and co-operating therewith by contact with the pulp blanket to express and to pick up liquid from the collected pulp blanket; said dewatering roll including a plurality of longitudinally directed, angularly spaced vanes located adjacent its periphery and defining a plurality of water-collecting

pockets, and an end plate closing said pockets but formed with holes admitting to each pocket and located in a common circle, for drainage; an air-pressure chest contacting the roll's end plate in position to include a number of holes immediately in advance of the roll's point of contact with the pulp blanket, in the sense of the roll's rotation, to expel undrained liquid picked up and collected within the roll's pockets; and a suction chest contacting the roll's end plate in position to include a number of holes in the vicinity of and immediately beyond the roll's point of contact with the pulp blanket, in the sense of the roll's rotation, to withdraw expressed liquid picked up and collected within the roll's pockets.

6. In a pulp-forming machine, in combination with a pulp vat and with a mold of large diameter rotative within the pulp vat to collect a peripheral blanket of pulp and to carry the same to a level above the liquid within the vat, and with a dewatering roll of small diameter located at the uprunning side of the mold's periphery and co-operating therewith by contact with the pulp blanket to express and to pick up liquid from the collected pulp blanket; said dewatering roll including a plurality of longitudinally directed, angularly spaced vanes located adjacent its periphery and defining a plurality of water-collecting pockets, and an end plate closing said pockets but formed with holes admitting to each pocket and located in a common circle, for drainage; air pressure means acting through said holes to expel water from the roll's pockets in advance of next contact of the corresponding peripheral portion of the roll with the pulp blanket, a trough located in the notch between the uprunning lower periphery of the roll and the uprunning upper periphery of the mold, to catch water so expelled, and a drain from said trough to lead the water caught therein to a point where it will not drop back upon the pulp blanket collected on the mold.
